United States Patent Office

Des. 180,731
Patented Aug. 6, 1957

180,731

GLOVE

Julius A. Higier, Johnstown, N. Y.

Application November 28, 1956, Serial No. 43,976

Term of patent 3½ years

(Cl. D3—11)

I claim:

The ornamental design for a glove, substantially as shown.
